United States Patent Office

Des. 211,760

Patented July 23, 1968

211,760

OVERHEAD PROJECTOR

Jack P. Blomgren, Maplewood, and George W. Brewitz, Burnsville, Minn., assignors to Minnesota Mining and Manufacturing Company, St. Paul, Minn., a corporation of Delaware

Filed July 11, 1967, Ser. No. 7,756

Term of patent 14 years

(Cl. D61—1)

FIG. 1

FIG. 2

FIG. 3

FIG. 4

FIG. 5

FIG. 6

FIGURE 1 is a front elevational view of an overhead projector, showing our new design;

FIGURE 2 is a rear elevational view;

FIGURE 3 is a top plan view;

FIGURE 4 is an elevational view of the left side;

FIGURE 5 is an elevational view of the right side; and

FIGURE 6 is a plan view of the bottom of the overhead projector.

The grille of FIG. 2 is continuous over the area outlined.

We claim:

The ornamental design for an overhead projector, substantially as shown and described.
